UNITED STATES PATENT OFFICE.

JAMES SIRACUSA, OF BUFFALO, NEW YORK, ASSIGNOR TO ROCK ASPHALT & CONSTRUCTION CO., INC., OF BUFFALO, NEW YORK, A CORPORATION OF NEW YORK.

ASPHALT CUTTER.

Application filed March 11, 1924. Serial No. 698,394.

To all whom it may concern:

Be it known that I, JAMES SIRACUSA, a citizen of the United States, residing at Buffalo, in the county of Erie and State of

5 New York, have invented a new and useful Improvement in Asphalt Cutters, of which the following is a specification.

This invention relates to a hammer operating mechanism such as now commonly 10 employed in asphalt cutters of that type in which the cutting is effected by means of a hammer adapted to be lifted by power and to drop by gravity for driving the knife or blade thereon into the asphalt, although the 15 same may also be used for other purposes.

The objects of this invention are to provide means for controlling the operation of lifting and releasing the hammer so that the latter when free will be practically unrestrained by gearing and thus permit the 20 weight of the hammer to operate more effectively in driving the knife into the asphalt; also to quickly release the hammer from the lifting mechanism so that the hammer can 25 begin its descent instantly after such release and permit it to accelerate its downward movement rapidly and thus improve its driving blow on the knife; to so construct the means for coupling and uncoupling the 30 hammer lifting means with the power mechanism that this operation is effected quickly and with a minimum of friction and wear on the parts; and to provide means for accomplishing this purpose which are simple 35 and durable in construction, efficient and reliable in operation, and not liable to get out of order due to vibration and hard usage to which they are subjected.

In the accompanying drawings:

40 Figure 1 is a vertical transverse section of an asphalt cutter illustrating diagrammatically one machine in which my invention may be embodied. Figure 2 is a fragmentary top plan view of the hammer hoisting mechanism. Figure 3 is a side elevation 45

of the same. Figure 4 is a vertical transverse section taken on line 4—4, Fig. 3. Figure 5 is a horizontal section taken on line 5—5, Fig. 3. Figure 6 is a vertical transverse section taken on line 6—6, Fig. 50 2. Figures 7 and 8 are fragmentary vertical longitudinal sections taken on line 7—8, Fig. 6 and showing the parts in different 55 positions. Figure 9 is a vertical longitudinal section, on an enlarged scale, taken on

line 9—9, Fig. 5. Figures 10 and 11 are vertical longitudinal sections taken on line 10—11, Fig. 5 and showing the parts in different positions.

Similar characters of reference indicate 60 like parts throughout the several views.

The numeral 20 represents the frame or body of the car or vehicle upon which the asphalt cutting mechanism is mounted and transported while in use or from one piece 65 of work to another for which purpose this frame is mounted on wheels 21 and may be propelled in any suitable manner.

Movable vertically in suitable upright 70 ways 22 on the main frame is a hammer or sliding weight 23 which is provided on its underside with a knife or blade 24 adapted to strike the asphalt under the weight of a blow of the hammer and cut a slit or groove into the same so as to permit the same to be 75 subsequently easily removed from the street in case of repairs or when preparing the same for digging a trench to receive sewer gas, water pipes or electric conduits.

This lifting of the hammer is preferably 80 effected by a chain belt 25 passing with its upper turn over a guide pulley 26 on top of the main frame and having the lower end of its outer stretch connected with the hammer and the lower end of its inner 85 stretch connected with the periphery of a hoisting drum 19. The latter is mounted loosely on a horizontal hoisting shaft 27 journaled in suitable bearings 28, 29 on the main frame and is adapted alternately to be 90 connected with a power mechanism whereby the same is turned forwardly for causing the lifting chain to wind thereon and lift the hammer and to be disconnected therefrom to permit the drum to turn backwardly and the hammer to descend as the lifting chain unwinds from the drum. For this purpose a clutch mechanism is provided which is constructed as follows:

The numeral 30 represents a driven clutch 100 wheel or disk which is formed integrally or connected with the hoisting drum and provided on one side with an annular clutch groove or jaw 31 which is of tapering form in cross section, and a driving clutch wheel or disk 32 secured to the hoisting shaft and provided on one side with an annular clutch, rib or jaw 18 of tapering form in cross section and adapted to engage the clutch 105 groove in the driven clutch disk. The driv- 110

ing clutch disk turns continuously in the same direction when the machine is in operation by power derived from any suitable source. For instance, as shown in Figure 1, this may be accomplished by means of a gas engine 33 mounted on the lower part of the main frame and having its shaft 34 provided with a gear wheel 35 from which motion is transmitted to a gear wheel or rim 36 on the driving clutch disk by means of an intermediate gear wheel 37 mounted on the main frame. Upon moving the driven clutch disk axially toward the driving clutch disk these two disks will be coupled and the hoisting drum will be turned forwardly so as to wind the hoisting chain thereon and lift the hammer. Upon moving the driven disk axially away from the driving disk these disks will be uncoupled and allow the hammer to fall during which time the lifting chain unwinds from the hoisting drum and the latter is turned backwardly. The clutch disks are yieldingly held apart by a spring 38 interposed between the same and the rotation of the drum is either controlled or prevented by a brake band 39 adapted to be moved into and out of gripping engagement with the periphery of the driven clutch disk by means of a lever 40 mounted on the main frame.

The movement of the driven clutch disk toward the driving clutch disk is effected by the following means:

The numeral 41 represents an abutment collar secured to the hoisting shaft on that end thereof opposite the end which is connected with the driving clutch disk. Between the abutment collar and the hub of the hoisting drum and driven clutch disk is arranged a pair of cam disks 42, 43, the opposing sides of which are in engagement and have the form of cams or wedges so that upon turning these cam disks forwardly or in one direction these disks will be spread apart in a direction lengthwise of the axis of the hoisting shaft while upon turning these disks backwardly or in the opposite direction the same will be permitted to approach each other. The thrust thus exerted by the cam disks upon turning the same forwardly is caused to move the driven clutch disk into engagement with the driving disk, this being preferably effected by interposing a ball thrust bearing 44 between the rear side of the cam disk 42 and the hub of the hoisting drum and driven clutch disk and a similar thrust ball bearing 45 between the thrust and collar 41 and the rear side of the cam disk 43. In order to permit of adjusting the relation of the cam disks relatively to each other and to take up wear on the parts between the thrust collar 41 and the driving clutch disk, means are provided which preferably consist in providing the outer side of the cam disk 43 with an ad-

justing sleeve 46 having a screw connection with the cam disk 43 and engaging the outer ball bearing 45, as shown in Figures 2 and 4. Turning of the cam disks forwardly and backwardly relatively toward each other is effected by means which comprise a vertically swinging shifting lever 47 pivoted at one end on the main frame, two links 48, 49 having their upper ends pivotally connected with the shifting lever while their lower ends are respectively pivotally connected with the cam disks 42, 43, on diametrically opposite sides of the axis about which they turn, as shown in Figures 7 and 8. The cam faces of the cam disks are so constructed that upon raising the shifting lever 47, as shown in Figure 7, the cam disks are permitted to approach each other and uncouple the clutch so as to release the drum and permit the hammer to drop, while upon lowering the shifting lever, as shown in Figure 8, the cam disks will be spread to cause the driving and driven clutch disks to be coupled or closed and the drum to lift the hammer.

The raising and lowering of the shifting lever is effected automatically and periodically so that the clutch will be opened the instant the hammer reaches the desired height and the clutch is again closed during the last part of the downward stroke of the hammer preparatory to again elevating the same. This operation is effected by an automatic controlling mechanism which is constructed as follows:

The numeral 17 represents a horizontal controlling shaft journaled transversely in suitable bearings 15, 16 on the main frame so that the same is parallel with the clutch and drum shaft, as shown in Figures 2 and 3. The shaft is yieldingly held against turning by a frictional resisting device which in its preferred form, as shown in Figures 2 and 3, comprises a fixed friction disk 51 arranged on the bearing 15, a movable friction disk 52 engaging the fixed friction disk and connected by a spline 53 with the controlling shaft so as to be free to move lengthwise on this shaft but compelled to turn therewith, and a spring 54 interposed between the rear side of the movable friction disk and an abutment collar 55 secured to the controlling shaft.

The free end of the cam disk shifting lever is preferably constructed in the form of a fork and its upper and lower tines or branches 56, 57 engage with opposite sides of a rotary controlling or lifting cam 58 which is secured to the controlling shaft. A ball thrust bearing 59 is interposed between the hub of the lifting cam 58 and the adjacent bearing 16 on the main frame for the shaft 17.

The numeral 60 represents a driven controller sprocket wheel mounted loosely on

- the controlling shaft and 61 represents a chain belt passing around this driven sprocket wheel and a driving controller sprocket wheel 62 on the hoisting drum.
- 5 On one side of the driven controller wheel 60 the same is provided with a tappet 63 which preferably has the form of an eccentric which is adjustably mounted on the controller wheel 60 by means of a pivot and 70
- 10 clamping screw 64. This tappet is adapted to engage alternately with opposite sides of a tappet arm 65 secured to the controller shaft 17.

The operation of this mechanism is as 15 follows:—

- In Figures 3, 4, 6, 7 and 9 the parts are shown in the position which they occupy when the clutch is released and the hammer has been permitted to drop by gravity and 20 produce an incision of the knife in the asphalt. At this time the lifting cam 58 has its salient part in its highest position, the tappet engages with the underside of the tappet arm on one side of the axis of the 25 controller shaft, and links are raised by the controlling lever and turn the cam disks so that the low part of the cam face on each of these disks is opposite the high part of the cam face of the other cam disk. The 30 parts have been brought to this position by the forward rotation of the hoisting drum while the same was coupled with the motive power and the hammer was being lifted, the direction of movement of the drum at 35 this time being indicated by the arrow in Figure 2. The instant the hammer has reached the highest position which has been predetermined and the drum has been disconnected from the power mechanism by 40 uncoupling of the clutch the hammer is perfectly free and drops quickly for driving its knife with a hammer blow into the asphalt. During this drop of the hammer the hoisting chain unwinds from the drum and 45 turns the latter backwards. This also causes the tappet to be turned backwardly by reason of the wheel 60 on which it is mounted being connected by the chain belt 61 and driving sprocket wheel 62 with the 50 drum. As the driven sprocket wheel 60 turns backwardly the tappet carried by the same first moves idly out of engagement from the underside of the tappet arm and independently therefrom until the tappet has 55 made nearly a complete turn about the axis of the controller shaft and thus engages with the upper side of the tappet arm. Thereafter the tappet during its continued backward rotation carries backwardly with 60 it the tappet arm until the latter has made one half a rotation about the axis of the controller shaft, and has carried the same from the position shown by full lines in Figure 9 to the position shown by dotted 65 lines in the same figure. As a result of the

action the lifting cam is reversed so that its salient part is carried from a position in which it is uppermost, as shown by full lines in Figure 9, to a position in which the same is lowermost, as shown by dotted lines in 70 the same figure, thereby causing the lifting lever to be lowered and the cam disks to be turned so that the high parts of their cam faces oppose each other.

In consequence of this the clutch is again 75 coupled and the drum is again turned forwardly and winds the hoisting chain thereon for lifting the hammer. The parts are so timed that this uncoupling occurs during 80 the last part of the downward movement of the hammer, so that the clutch is coupled and lifting of the hammer commences immediately after the knife strikes the asphalt. This upward movement of the hammer continues until the drum during its forward or 85 winding movement has first moved the tappet idly from the underside of the tappet arm, as shown by dotted lines in Figure 9, nearly a full turn about the axis of the controller shaft until it engages with the 90 upper side of the arm after which the tappet and tappet arm move forwardly together until the latter has turned 180 degrees and the lifting cam 58 has been moved from the pendent position shown by dotted lines in 95 Figure 9, to the upstanding position shown by full lines in the same figure. When the lifting cam 58 reaches this position the lifting lever turns the cam disks in a direction for removing the thrust against the driven 100 clutch disk and permitting the spring 38 to open the clutch and thus release the hoisting drum so that it can turn backwardly and permit the hoisting chain to unwind therefrom under the pull of the hammer which at this time is free to descend and deliver a 105 blow of its blade into the asphalt surface of the pavement. During the continued use of the machine this cycle of operation is 110 repeated continuously in the manner described.

In the drawings the driving controller sprocket wheel 62 is represented as being somewhat larger than the driven controller sprocket wheel 60 but the relative size of 115 these wheels may be altered as required depending on the size of the hoisting drum and the rate of speed at which the hoisting is to be effected.

By adjusting the eccentrically shaped tappet about its pivot and clamping screw on the driven controller sprocket wheel the height to which the hammer is lifted at each stroke before it is released may be varied and thus permit of adjusting the blow of 120 the hammer according to the hardness of the asphalt, the same being comparatively hard and requiring a heavier blow of the hammer in cold weather, while in warm weather the same is comparatively soft and therefore a 125

lighter blow of the hammer will suffice to drive the knife the requisite depth into the asphalt.

Owing to the quick release of the drum 5 from the power mechanism when the hammer reaches the top of its stroke it is possible for the hammer to begin its descent instantly and owing to the complete disconnection thus effected between these parts it 10 is possible for the hammer to drop without undue restraint and thus rapidly accelerate its speed and deliver the most effective blow, thereby enabling the machine to work with greater efficiency and increase the amount of 15 work done within a given time, whereby a corresponding saving in cost is effected. Furthermore the several parts of this machine are of simple construction, they are not liable to get out of order and can readily 20 be replaced when worn.

Obviously this hammer operating mechanism can be used in analogous machines, such as pile drivers, and forging machines.

I claim as my invention:

25 1. A hammer operating mechanism of the character described comprising a driving clutch member, a driven clutch member adapted to engage said driving clutch member, a controlling shaft which is rotated by motion derived from said driven clutch member, and means actuated by said controlling shaft and operating to engage said clutch members, comprising a cam mechanism operating on said driven clutch member, a rock lever connected with said cam mechanism, and a controlling cam mounted on said controlling shaft and engaging with said rock lever.

40 2. A hammer operating mechanism of the character described comprising a driving clutch member, a driven clutch member adapted to engage said driving clutch member, a controlling shaft which is rotated by motion derived from said driven clutch member, and means actuated by said controlling shaft and operating to engage said clutch members comprising two rotary cams having opposing cam faces which engage with each other and one of said cam disks 45 exerting a thrust against said driven clutch disk, an abutment which receives the thrust of the other cam disk, a rock lever connected with said cam disks on opposite sides of the axis of said disks, and a controlling cam 50 arranged on said controlling shaft and engaging with said lever.

55 3. A hammer operating mechanism of the character described comprising a driving clutch member, a driven clutch member and means for pressing said driven member toward said driving member and releasing the same including a controlling shaft, a cam mechanism adapted to press said driven clutch member toward said driving member, 60 a rock lever connected with said cam mecha-

nism, a controlling cam secured to said shaft and engaging with said rock lever, a tappet rotatably mounted on said shaft, means for rotating said tappet, and a tappet arm secured to said shaft and adapted to be engaged by said tappet.

70 4. A hammer operating mechanism of the character described comprising a driving clutch member, a driven clutch member and means for pressing said driven member toward said driving member and releasing the same including a controlling shaft, a cam mechanism adapted to press said driven clutch member toward said driving member, a rock lever connected with said cam mechanism, a controlling cam secured to said shaft and engaging with said rock lever, a driving wheel connected with said driven clutch member, a driven wheel mounted on said shaft, a belt passing around said driving and driven wheels, a tappet arranged on said driven wheel and a tappet arm secured to said shaft and adapted to engage with said tappet.

75 5. A hammer operating mechanism of the character described comprising a driving clutch member, a driven clutch member and means for pressing said driven member toward said driving member and releasing the same including a controlling shaft, a cam mechanism adapted to press said driven clutch member toward said driving member, a rock lever connected with said cam mechanism, a controlling cam secured to said shaft and engaging with said rock lever, a rotatable support on said shaft, means for rotating said support from said driven clutch member, an eccentric tappet pivotally mounted on said support and capable of adjustment about its pivot, and a tappet arm arranged on said shaft and adapted to be engaged by said tappet.

80 6. A hammer operating mechanism of the character described comprising a driving clutch member, a driven clutch member and means for pressing said driven member toward said driving member and releasing the same including a controlling shaft, a cam mechanism adapted to press said driven clutch member toward said driving member, a rock lever connected with said cam mechanism, a controlling cam secured to said shaft and engaging with said rock lever, a tappet rotatably mounted on said shaft, means for rotating said tappet, a tappet arm secured to said shaft and adapted to be engaged by said tappet, and means for retarding the rotation of said shaft.

85 7. A hammer operating mechanism of the character described comprising a driving clutch member, a driven clutch member and means for pressing said driven member toward said driving member and releasing the same including a controlling shaft, a cam mechanism adapted to press said driven clutch member toward said driving member, 90 a rock lever connected with said cam mechanism, a controlling cam secured to said shaft and engaging with said rock lever, a tappet rotatably mounted on said shaft, means for rotating said tappet, a tappet arm secured to said shaft and adapted to be engaged by said tappet, and means for retarding the rotation of said shaft.

- clutch member toward said driving member, a rock lever connected with said cam mechanism, a controlling cam secured to said shaft and engaging with said rock lever, a 5 tappet rotatably mounted on said shaft, means for rotating said tappet, a tappet arm secured to said shaft and adapted to be engaged by said tappet, and means for retarding the rotation of said shaft comprising a 10 stationary friction disk surrounding said shaft, a movable friction disk slidable lengthwise on the shaft but compelled to turn therewith, and a spring for pressing said movable disk against said stationary 15 disk.
8. A hammer operating mechanism of the character described comprising a driving clutch member, a driven clutch member and means for pressing said driven member to- 20 ward said driving member and releasing the same including a controlling shaft, a cam mechanism adapted to press said driven clutch member toward said driving member, a rock lever connected with said cam mech- 25 anism, a controlling cam secured to said shaft and engaging with said rock lever, a tappet rotatably mounted on said shaft, means for rotating said tappet, a tappet arm secured to said shaft and adapted to be en- 30 gaged by said tappet, and means for retarding the rotation of said shaft comprising a stationary friction disk surrounding said 35 shaft, a movable friction disk slidable lengthwise on the shaft but compelled to turn therewith, a spring for pressing said movable disk against said stationary disk, and an abutment for said spring on said shaft.
9. A hammer operating mechanism of the character described comprising a driving 40 clutch member, a driven clutch member and means for pressing said driven member toward said driving member and releasing the same including a controlling shaft, a cam mechanism adapted to press said driven 45 clutch member toward said driving member, a rock lever connected with said cam mechanism, a controlling cam secured to said shaft and engaging with said rock lever, a tappet rotatably mounted on said shaft, 50 means for rotating said tappet, a tappet arm secured to said shaft and adapted to be engaged by said tappet, and means for retarding the rotation of said shaft comprising a stationary friction disk surrounding said 55 shaft, a movable friction disk slidable lengthwise on the shaft but compelled to turn therewith, a spring for pressing said movable disk against said stationary disk, and a thrust bearing which resists length- 60 wise movement of said shaft in a direction opposite to the longitudinal movement of said movable friction disk.

In testimony whereof I affix my signature.

JAMES SIRACUSA.
